FIG. 2

FIG. 3

FIG. 1

FIG. 4

FIG. 5

FIGURE 1 is an elevational view of a drinking cup, showing our new design.

FIGURE 2 is a top plan view;

FIGURE 3 is a fragmentary sectional view taken along the line 3—3 of FIGURE 1;

FIGURE 4 is a fragmentary sectional view taken along the line 4—4 of FIGURE 1; and

FIGURE 5 is a fragmentary sectional view taken along the line 5—5 of FIGURE 1.

The characteristic feature of our design lies in a plurality of adjacent hemispherical circumferential beads which are formed in the drinking cup sidewall, are smaller than the rolled brim surrounding the open cup end, and are spaced from the brim by a slightly outwardly flaring upper portion of the sidewall.

We claim:

The ornamental design for drinking cup, substantially as shown and described.
